(57) **CLAIM**

The housing for a stick-type vacuum cleaner, as shown and described.

DESCRIPTION

FIG. 1 is a perspective view of a housing for stick-type vacuum cleaner showing our new design;

FIG. 2 is an enlarged perspective view of the housing alone;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a top plan view thereof; and,

FIG. 8 is a bottom plan view thereof.

The components shown in dotted lines in FIGS. 1-8 form no part of the claimed design.
